R. E. JACKMAN

SHOE FOR LIFTS AND THE LIKE

Filed May 23, 1923

- FIG 1 -

- FIG 2 -

Royston Eric Jackman
INVENTOR;

By *Otto Munk*
his Attorney.

UNITED STATES PATENT OFFICE.

ROYSTON ERIC JACKMAN, OF ROSE PARK, SOUTH AUSTRALIA, AUSTRALIA.

SHOE FOR LIFTS AND THE LIKE.

Application filed May 23, 1923. Serial No. 640,879.

To all whom it may concern:

Be it known that I, ROYSTON ERIC JACKMAN, a subject of His Majesty the King of Great Britain, residing at Rose Park, South

5 Australia, Commonwealth of Australia, have invented certain new and useful Improvements in a Shoe for Lifts and the like, of which the following is a specification.

My invention relates to an improved shoe 10 and is principally designed for use in connection with electric lifts or elevators but is applicable to various types of mechanical runner of an analogous nature.

In connection with the shoes for the cages 15 and counterweights of lifts it has hitherto been customary to provide means for oiling or lubricating the shoe or block either by aid of a force feed screw cap or by ordinary oiling methods. It is found, however, that 20 in addition to the inconvenience of oiling or greasing the shoe and runner the accumulated grease collects dust and grit and the frequent lubrication of the appliance becomes ineffective.

25 In my invention I entirely dispense with the grease cap or oil holes and in lieu thereof I form the inner or running surface of the shoe with a series of recesses, grooves or depressions, but preferably grooves are used 30 in horizontal parallel alignment with each other and are filled with graphite which forms an antifriction wearing surface level with the wearing surface of the metal from which the shoe is cast.

35 But in order that my invention may be more clearly understood I will now describe the same by aid of the accompanying illustrative drawings wherein:—

40 Fig. 1 is a side elevation of shoe in part section.

Fig. 2 is a plan of shoe in part section.

In each of the illustrations similar letters of reference are used to denote similar or corresponding parts wherever they occur.

45 In the drawings *a* is the metal casting or body of the shoe formed with the customary

extension or barrel *b* in which the screw threaded hole *c* is provided for attachment and adjustment of the shoe to the elevator cage or weight.

50

The interior of the shoe is turned or arched so as to enable it to be fitted in the usual manner to the guide rod or pillar, and within the turned portion I cut or cast a series of recesses, grooves or depressions which take the form of horizontal parallel grooves *d* which stop short of the diameter line of the turned or otherwise shaped portion as indicated by the presence of the block or solid portion *e* thus leaving narrow ridges *f* 55 of the solid metallic shoe material on both sides of the shoe between which are the graphite compound bearing areas *g* which may be arranged as illustrated.

I do not confine myself to any particular 60 size or depth of groove but I prefer to form the base or bottom of the grooves in the shape illustrated, but they may be rectangular, or the bottom or floor of the recesses may be reversely angled so as to form a dovetail 65 into which the graphite may be pressed and retained, the graphite being worked into a paste according to any suitable well known method or formula.

70 By using shoes or blocks of the nature described the wearing surfaces both of the shoe and the pillar become well polished and do not require the application of lubricating oil or grease.

75 I claim:—

A bearing shoe for elevator guideways comprising a body portion attachable to the elevator and having its bearing surface provided with parallel graphite containing grooves projecting to points short of the 80 ends of the bearing surface and disposed transversely of the axis of the guideway, the walls of the grooves being tapered inwardly from the surface to the bottom.

85 In testimony whereof I have affixed my 85 signature.

ROYSTON ERIC JACKMAN.
